[57] CLAIM

The ornamental design for a faucet, as shown and described.

DESCRIPTION

FIG. 1 is a perspective view taken from the top, front and left side of a faucet showing our new design; FIG. 2 is a left side elevational view thereof, the right side being a mirror image of the left side; FIG. 3 is a front elevational view thereof; FIG. 4 is a top plan view thereof; FIG. 5 is a rear elevational view thereof; FIG. 6 is a bottom plan view thereof; FIG. 7 is a top plan view of a second embodiment thereof, this embodiment being the same as the first embodiment except for the omission of the top cap; and, FIG. 8 is a left side elevational view of a third embodiment thereof, this embodiment being the same as the first embodiment except for the absence of the drain pull.

FIG. 1

FIG. 2

FIG. 3

FIG. 4

FIG. 5

FIG. 6

FIG. 7

FIG. 8
